UNITED STATES PATENT OFFICE.

EDWARD J. TOMLINSON, OF EAST ORANGE, NEW JERSEY, ASSIGNOR TO SPLITDORF ELECTRICAL COMPANY, OF NEWARK, NEW JERSEY.

PHONOGRAPH.

1,413,074.

Specification of Letters Patent. Patented Apr. 18, 1922.

Application filed July 5, 1919. Serial No. 308,840.

To all whom it may concern:

Be it known that I, EDWARD J. TOMLINSON, a citizen of the United States, residing at East Orange, in the county of Essex and State of New Jersey, have invented certain new and useful Improvements in Phonographs, of which the following is a specification.

This invention relates to electrically operated phonographs and as illustrated is particularly adapted for playing a record in the form of a plate or flat disk.

It is the principal object of my invention to provide a phonograph in which the sound record body is carried on a support electrically driven in such a manner as to insure a constant speed and quietness of operation.

In carrying out the principal object of my invention, I aim to secure a motor mechanism that is simple in construction and highly efficient in its operation.

It is another object of my invention to provide a starting and stop mechanism for the rotating support which is simple and positive in its operation.

Another object of my invention is to incorporate in the stopping mechanism means for stopping the turn-table shortly after the playing of the record has been completed.

In my application, Serial No. 288,386, filed April 7, 1919, and my application, Serial No. 301,101, filed May 31, 1919, I have shown and described two forms of electric motors suitable for phonograph purposes. My present invention is directed to a motor suitable for similar work but in which the operating mechanism is so arranged as to occupy a small amount of space along the axis of rotation and the construction, to be later described, is of a motor which I term as of the "pancake" type.

Other and further objects of my invention will be apparent to one skilled in this art, after a study of the specification and drawings annexed thereto, wherein—

Figure 1 is a bottom view of the sound record support body.

Figure 2 is a section on the line 2—2 of Figure 1.

Figure 3 is a plan view of a phonograph with the sound record support body shown in Figure 1 removed.

Figure 4 is a bottom view of Figure 3,

showing the starting and stopping mechanism.

Figure 5 is a partial view of Figure 4 but with the starting and stopping mechanism in a different position.

Figure 6 is a detail view of the automatic stopping mechanism.

Figure 7 is a diagrammatic view of the wiring of the phonograph motor.

Referring now to the details, wherein like numbers refer to corresponding parts in the various views, 1 illustrates a frame to which is fastened a support ring 2 in any suitable manner, such as screws 3 passing through preferably sound deadening buffers 57. Support ring 2 carries an inductor ring 4 having a plurality of poles 5 on which windings 6 are mounted. The central part of the ring 2 has a hub 7 within which is secured a bearing for a driving shaft. The end of the hub 7 is adapted to fit a recess 8 within the collar 9 carried on the sound record support body 10. The part 9 has teeth 11 for a purpose hereinafter pointed out. The driving shaft (not shown) is adapted to be fastened to the member 10 in any suitable manner. The member 10 has an inductor ring 12 fastened thereto in any suitable manner, such as by screws 13. Inductor ring 12 has a plurality of pole pieces 14 which, when the member 10 is in operative position, are in magnetic cooperation with the pole pieces 5.

Carried on two of the arms 15 and 16 of the member 2 is a sliding bar 17 having slots 18 and 19 through which shoulder screws 20 pass. Fulcrumed at 21 on the frame is an operating handle 22, the inner end of which has a slot 23 adapted to engage a pin 24 that is fastened to the bar 17. Bar 17 also carries a clip 25 on which is pivoted a pawl 26 that is adapted to engage the teeth 11. Bar 17 also carries a block 27 preferably of insulating material which block acts on a spring 28 to move a circuit breaker contact 29 to a position where it may or may not be acted on by a cooperating contact 30, in a manner herein pointed out. The bar 17 also carries a spring 31 adapted to contact with a screw 32 carried on the frame of a relay 33. Relay 33 has a movable armature 34 that carries a spring having a shoulder 35 adapted to engage a finger 36 on the bar 17 in a manner here-

after pointed out. Lever 22 carries a clip 37 to which is fastened a friction block 38.

The frame 1 also supports a governing device 39, similar to that shown and described 5 in my co-pending application, Serial No. 288,385, filed April 7, 1919, and since this governor mechanism forms no part of my present invention, it will not be described further herein. On one arm of the ring 10 2 a condenser 40 is mounted while a double resistance coil 41 is carried on the frame 1.

Carried on the hub 7 is an adjustable circuit breaker plate 42. Plate 42 is preferably made of some good insulating material and 15 has mounted thereon a member carrying a stationary contact 30 and a movable member 43 carrying contact 29. The circuit breaker mechanism is similar in many respects to that shown and described in my copending 20 application Serial No. 301,101, filed May 31, 1919, and will not be described at length herein except that the cam member on the shaft for operating the movable member 43 is adapted to open and close the circuit 25 through the coils 6 when the pole pieces 14 are in proper relation to pole pieces 5 whereby all the coils 6 function to simultaneously act on the pole pieces 14 to produce rotation of the sound record support body.

30 In order that the motor may be stopped directly after the record has been played, I provide automatic stopping mechanism, part of which has already been described and the balance of which is carried on the tone arm 35 44. The part carried by the tone arm consists of a ring 45 fastened to the tone arm in any suitable manner. To the ring 45 is attached a member 46 and fastened to the member 46 is a finger 47, same being connected to the member 46 by means of a spring washer 48, screw 49 and nut 50, whereby a friction joint is obtained. The finger 47 is adapted to make contact with the central post 51 (see Figure 7) which 45 holds the sound record support body 10 on the driving shaft, and which together with the tone arm comprises a portion of the circuit for the automatic stopping mechanism.

Considering now the operation of my phonograph motor, it will be understood that 50 normally the parts are in the position shown in Figure 4, wherein the lever 22 is held in the non-running position by spring 53 in which position the friction member 38 is in engagement with the circular member 54 carried by the member 10. When the lever 22 is in the position shown in Figure 4, it will be noticed that the end of member 28 engages the end of spring 43 through the medium of block 27 thereby moving the member 43 so that the contact 30 is out of engagement with the contact 29 thereby holding open the circuit through the coils 6 thus utilizing the circuit breaker as a switch. On 55 moving the lever 22 to the position shown in

Figure 5, the block 27 is carried to a position whereby the end of spring 28 is withdrawn from engagement with the spring 43 allowing the contacts 29 and 30 to come into association one with the other whereby the 70 spring 43 may be acted on by the cam to open and close the circuit through the coils 6 for applying current impulses to the motor at the proper time. As the block 27 reaches the fully operated position the finger 36 drops behind the notch 35 carried on the movable armature 34 of relay 33. This holds the bar 17 in the position shown in Figure 5, at the same time the contact is closed between the spring 31 and screw 32 which are 80 used to open and close the circuit instead of at the point where the finger 36 engages the spring having notch 35 as the breaking of the circuit at this latter place may burn the spring having notch 35 or the finger 36 and 85 roughen them to such an extent as to interfere with their sliding operation, as it will be understood that a manual pull at the end of the lever 22 will cause the finger 36 to come out of engagement with the notch 35. Operation of the lever 22 as above described 90 also operates the pawl 26 so that the finger 55 formed thereon will engage the ratchet teeth 11 to give the sound record support body a starting impulse at the same time the 95 brake block 38 is removed from engagement with the circular member 54. Before operating the lever 22 for starting the motor, as above described, it will be understood that the record disk has been placed on the sound 100 record support body 10 and the tone arm 44 moved over so that it is seen that the finger 47 will engage with post 51 which is after the needle carried by the tone arm has finished playing the record. The tone arm is 105 then carried to the starting position and the lever 22 operated. When the tone arm 44 reaches said predetermined point, whereby the finger 47 engages the post 51 a circuit is completed through the relay 33 which will 110 be readily observed and the relay 33 will operate the armature 34 releasing the finger 36 from engagement with the notch 35 allowing the spring 53 to return the starting lever and parts to the position shown in Figure 4, in which position the circuit through the windings 6 is open and a brake applied to the sound record support body in a manner previously described.

Referring to the diagrammatic wiring 120 shown in Figure 7, it is seen that the circuit breaker has a condenser 40 and resistance 41 wired in shunt therewith and a resistance 52 in shunt with the governor 39. The governor 39 functions to control the speed of the 125 phonograph motor which speed may be adjusted by operation of the button 56.

It will be understood that in a device of this character numerous changes and alterations may be made in the construction of the 130

various parts without departing from the spirit of my invention and the scope of the appended claims.

Having thus described my invention, what

5 I claim is:—

1. In a phonograph in combination with a rotatable sound record support and electromagnetic motor means therefor, of an intermittently operated circuit breaker for said 10 motor means comprising a fixed member and a movable member, and a controlling member for said circuit breaker operable upon movement in one direction to engage the movable member to maintain the contact open, and upon movement in the opposite direction to release said movable member, and electromagnetically releasable means 15 latching said controlling member in said member releasing position.
2. In a phonograph, in combination with a rotatable sound record support of electromagnetic driving means therefor, a circuit breaker in the circuit of the electromagnetic driving means intermittently operated upon 20 rotation of the support, and a controller under the control of a latch operative to simultaneously apply a braking force to the support and to open the circuit breaker upon release from said latch.
3. In a phonograph, a rotatable sound record support, and electromagnetic driving means therefor, of an intermittently operated 25
4. In a phonograph, a rotatable sound record support, and electromagnetic driving means therefor, of an intermittently operated circuit breaker for said driving means operated upon rotation of the support, a controlling bar slidable longitudinally to 30 maintain the circuit breaker open in one direction and to permit the circuit breaker to close in the opposite direction, means tending normally to maintain the bar in position to maintain the circuit breaker open, 35 and electromagnetically releasable latching means, the circuit of which is controlled by said bar, for maintaining the bar in the other position.
5. In a phonograph, a rotatable sound record support, and electromagnetic driving means therefor, of an intermittently operated circuit breaker for said driving means operated upon rotation of the support, a controlling bar slidable longitudinally to 40 maintain the circuit breaker open in one direction and to permit the circuit breaker to close in the opposite direction, a member on the bar to impart movement to the support upon movement of the bar in said opposite direction, means tending normally to 45 maintain the bar in position to maintain the circuit breaker open, and electromagnetically releasable latching means, the circuit of which is controlled by said bar, for maintaining the bar in the other position.

In witness whereof, I affix my signature.

EDWARD J. TOMLINSON.
